CLAIM

(22) Filed: **Sep. 3, 2002**

The ornamental design for an infrared camera including a slave monitor with system control, as shown.

(30) **Foreign Application Priority Data**

DESCRIPTION

Mar. 1, 2002 (SE) 02-0396

FIG. 1 is a right side elevational view of an infrared camera including a slave monitor with system control, showing our new design;

(51) LOC (7) Cl. **16-01**

FIG. 2 is a left side elevational thereof;

(52) U.S. Cl. **D16/202**

FIG. 3 is a top plan view thereof;

(58) Field of Search D16/200–206;
348/373–376; 358/906; 396/535, 540, 541

FIG. 4 is a bottom plan view thereof;
FIG. 5 is a front elevational view thereof; and,
FIG. 6 is a rear elevational view thereof.
